CLAIM

The ornamental design of the portable communication display device, as shown and described.

DESCRIPTION

FIG. 1 is a front right perspective view of a portable communication display device showing the new design. A

connector is shown in broken line;
FIG. 2 is a front view of the portable communication display device;
FIG. 3 is a right view of the portable communication display device;
FIG. 4 is a top view of the portable communication display device;
FIG. 5 is a rear view of the portable communication display device;

FIG. 6 is a left view of the portable communication display device. A display pod is shown rotated in broken line; and, FIG. 7 is a bottom view of the portable communication display device.

The broken line showings of a connector and, a display housing or pod, are for illustration purposes only and form no part of the claimed design.
